(57) **CLAIM**

The ornamental design for a panel adapter for voltage and current measurement, as shown and described.

DESCRIPTION

FIG. 1 is a bottom, front, left side perspective view of a panel adapter for voltage and current measurement showing our new design.

FIG. 2 is a top, rear, right side perspective view thereof.

FIG. 3 is a front elevation view thereof.

FIG. 4 is a left side elevation view thereof.

FIG. 5 is a right side elevation view thereof.

FIG. 6 is a rear elevation view thereof.

FIG. 7 is a bottom plan view thereof; and,

FIG. 8 is a top plan view thereof.

The broken lines in the figures illustrate portions of the panel adapter for voltage and current measurement that form no part of the claimed design. The panel adapter for voltage and current measurement has a hinged cover shown in an open position, though the claimed design encompasses alternate positions of the hinged cover as the cover is rotated about the hinge axis from the open position to a closed position.
